UNITED STATES PATENT OFFICE.

CHARLES S. STARR, OF ELMIRA, NEW YORK.

PACKER FOR HAY-PRESSES.

No. 903,021.

Specification of Letters Patent.

Patented Nov. 3, 1908.

Application filed December 16, 1907. Serial No. 406,798.

To all whom it may concern:

Be it known that I, CHARLES S. STARR, a citizen of the United States, and resident of Elmira, in the county of Chemung and State 5 of New York, have invented certain new and useful Improvements in Packers for Hay-Presses, of which the following, with reference to drawings, is a description thereof.

My invention relates to that class of devices attached to hay presses, as assistant means to pack the hay in the chute of the press, previous to the final action of the press in making the bale of hay, the object being to make an effective and easily operated device, doing the work of the pressmen in having to jump down upon and tramp the hay while filling the press chute, and providing for convenient lateral withdrawal of the press bar of my invention, from within the 20 bale of hay and press chute during the operation.

In the accompanying drawings I have shown an upright press with my invention attached thereto, but wish it understood that 25 I do not confine myself in its use to this style of press, but that the same may be used in various styles of presses, and in various ways without departing from the spirit of my invention when used for the appointed pur- 30 poses.

In the drawings Figure 1 is a perspective elevation of portions of a hay press with my complete invention attached thereto. Fig. 2 is a view in elevation of a press with the 35 cover and one of the doors at the top of the press open, and a portion of the front wall broken away, with parts of my packer attached to the press and having the hay pressed to the bottom and ready to be re- 40 filled again over the press bar, and from which position as shown the said press bar may be removed to the left, when the final action of the press may begin from the bottom upward with the press closed at the top 45 for that purpose. Fig. 3 is a sectional plan view of the lower part of one of the packer standards to more fully illustrate the locking mechanism for the rack bars. Fig. 4 is a view in elevated plane of the same, but with 50 the cap plate of the standard removed. Fig. 5 is a side view with a broken cross section of the removable press bar.

Referring to the drawings 1 represents a box or standard having near its lower part a 55 laterally extended base flange 2 by means of

which it is bolted, with a like standard, in upright position about midway on each of the opposite top rails 3 of the frame of the press.

Running in a groove 4 on the inner side of these standards in longitudinal direction and down into grooves 5 of the walls of the press inside, and covered over by the cap plates 6, are the rack plunger bars 7, these rack bars have notches 8 nearly throughout their length which shoulder at right angles into the bar, and at their lower ends are bisected with a vertically directed slot 9 opening from the end of the bar, and in direction across the press from one bar to the other, thus fitted to 70 rest on and over astride the tongue of a reverted T shaped press bar 10 running across under the ends of the rack bars 7. The ends of the said press bar 10 are notched to form shoulders 11 and 12 on its tongue portion at 75 either end into which the rack bars are seated, and are thus held from springing inward. One end of the press bar tongue is extended slightly beyond its notched shoulder, and has a hole 13 through it for inserting a hay 80 hook, or otherwise obtain hold to withdraw said press bar endwise through the opening 14 through the side wall of the press.

Between laterally projecting bosses of the cap plate 6 and the standard 1 on the pin 15 85 is pivoted a lever 16 which passes through an open portion 17 of the standard along side of the rack bar and is extended into a handle of considerable length away from the standard, and has pivoted to it a downwardly hanging 90 pawl 18 pivoted on a pin 19 fixed in the lever close to the rack bar, and into the notches of which the pawl is fitted to drive said rack plunger bars forcibly downward, as the lever 95 is swung or operated.

A spring 20 seated against the pawl below its journal and back into a raised portion of the handle, serves to keep the pawl into proper engagement with the rack bar. To hold said pawl out of engagement, when it is 100 desired to slide the rack bars upward, I have provided that the point or free end of the pawl can be set to rest in the notch 21, in the base flange 2 of the standard, under the weight of the handle lever to hold it there. 105

22 represents a catch or locking bolt fitted to slide in a groove 23 cut laterally in the standard, and to and from connection with the rack bar notches, under the action of a spring controlled lever 24 which is pivoted to 110

the extended part of the cap plate on a fixed bolt 25, and has its lower end connected by slot and pin 26 to the outer end of the locking bolt. Said lever 24 above its pivot is extended into a handle and has attached to it a spring 27 the lower end of which spring is so fixed and stationed to the supporting top rail of the press, to draw on the lever, so it will play the locking bolt inward a little more than the distance of the depth of the notches in the rack bar, thus making the catch or locking bolt act automatically to travel from notch to notch of said bar and lock same in any downward position, but when the lever 24 is thrown so as to bring the spring to draw over on the inner side of its pivot, the catch bolt is thereby pulled outward and will so remain out of connection with the notches of the rack bar.

20 Through the side wall of the press to which my invention may be attached I provide for a slot or opening 14 through which the press bar may be removed endwise from within the press and be again ready for use at the top in the following operation.

25 The press being filled with hay as snugly as possible, the little levers 24 are thrown to hold the catch bolt out, and the pawls 18 are swung out into their retaining notches under weight of the levers. The rack plunger bars are now lifted to the top of the press, and the press bar laid on the hay under them, the catch bolt is thrown inward by its lever, and the two hand levers 16 are jointly operated, 30 forcing the press bar down by the little pawls springing into the notches of the rack bars, until the press bar comes below the opening 14. The press is now again filled with hay to the top and the cover 28 is slid home under the top rails 3 of the press. The rack bars are now released of pressure and the press bar 35 withdrawn, and the press levers at the bottom put in action which lifts the bottom press board 29 upward confining the hay in a bale at the top where it may be wired and removed through the door 30 with the cover

slid off, when the process may again be repeated.

What I claim as new and desire to secure by Letters Patent is:—

1. In a hay press, a packer consisting of grooved standards rack bars arranged to travel therein, means for actuating the rack bars, a press bar removably connected to the rack bars, and means provided for withdrawing the press bar outwardly through the side wall of the press. 55

2. In a hay press, a packer, comprising rack bars provided with notches means for holding and guiding the rack bars, and means for engaging the notches to drive the bars forward, a press bar removably connecting the rack bars, and means for permitting the press bar to be withdrawn out endwise from within the press. 60

3. In a hay press, hay packer standards having flanged bases adapted to be bolted to the press rails, notched bars working in the standards, a T press bar connecting the notched bars, means for engaging the shoulders of the notches to actuate the press bar and coöperating means to lock the bars as they are advanced into the press. 65

4. In a hay press, hay packer standards, notched bars held by the standards and having their lower ends slotted, a T shaped press bar seated in said slots, levers with pawls fixed in the standards for advancing the notched bars, and lever and spring operated locking bolts for said notched bars, substantially as described. 70

5. In a hay packer for hay presses, a press bar arranged for pressing hay within the press, means for actuating said press bar to press the hay, an opening in the press wall 85 through which said press bar may be withdrawn from within the press.

CHARLES S. STARR.
